UNITED STATES PATENT OFFICE.

ALOIS STAUBACH, OF CRESTLINE, OHIO.

SAW SET.

Application filed February 1, 1923. Serial No. 616,297.

To all whom it may concern:

Be it known that ALOIS STAUBACH, a citizen of the United States of America, residing at Crestline, in the county of Crawford and State of Ohio, has invented new and useful Improvements in Saw Sets, of which the following is a specification.

The object of the invention is to provide a simple and efficient manually operable saw set particularly adapted for small or hand saws although available for use in connection with power driven saws, and designed not only to secure accuracy and uniformity in the setting of the teeth but to accomplish the desired object with the utmost facility and rapidity; and with these objects in view the invention consists in a construction and combination of parts of which a preferred embodiment is shown in the accompanying drawings, wherein:—

Figure 1 is a side view, and

Figure 2 is a longitudinal sectional view of a tool embodying the invention.

Figure 3 is a plan view of the same with the cap or cover plate removed.

Figure 4 is a detail view of the anvil detached.

The device consists of a hollow stock 10 which may be stamped or upstruck from sheet metal and is extended at one end in angular relation with the body portion of the casing formed thereby to provide a grip member 11, said stock being fitted with a removable cap or cover 12 for completing a casing or housing in which the operating parts of the device are enclosed, and the stationary grip member 11 being supplemented by a movable grip member 13 pivoted as at 14 to the stock to complete a grip which may be grasped by the hand of the operator and squeezed in order to effect the operation of the plunger 15 carrying the setting bit 16 and mounted in suitable guides 17 and 18 in the stock. The grip members are of transversely telescoping construction to afford a convenient handle by which the tool may be manipulated with the sides thereof in overlapping relation to prevent pinching of the hand in the operation of the device.

The movable grip member carries an arm 19 which in connection with said grip member constitutes an operating lever having terminal connection with one arm of a bell-crank lever 20 fulcrumed at 21 in the stock and having its other arm connected with the

plunger 15. It is preferred to employ a pin and slot connection 22, 23 to connect the arm 19 with the bell-crank lever while the other arm of said bell-crank lever may be extended through a slot 24 in the rear end of the plunger.

The stock carries inner and outer jaws 25 and 26 between which the saw blade is adapted to be arranged in connection with the tooth setting operation, and the space between said jaws is invaded by the bit carried by the plunger 15 and which is movable subject to the retracting action of the spring 27 toward and from an anvil block 28 carried by the outer jaw 26 and revolvably adjustable to bring different portions of its operative face into the path of the bit 16. The operative face of the anvil block is provided with a graduated bevel to agree with different angular sets of the saw teeth, and the block is locked in its adjusted positions by means of a set-screw 29.

Also in connection with the saw receiving jaws there are arranged gauge blocks 30 carried by adjusting screws 31 and adapted to be disposed to limit the insertion of the saw blade into the space between the jaws so as to locate the proper portions of the saw teeth in the path of the bit 16.

In cooperative relation with the plunger which as above indicated is actuated by the movable member of the grip there is a saw blade clamp consisting of a slide 32 mounted in the stock with an up-turned ear 33 through an opening in which extends the plunger 15, said ear being arranged between a collar 34 and a pin 35 whereby motion is communicated to the side by the plunger. The side extends through a suitable guide 36 at the front end of the stock to also invade the space between the jaws 25 and 26 but with its forward end slightly in rear of the bit 16 so that it serves by contact with the side of the saw blade below the teeth 100 to prevent the tilting of the blade while the setting of the tooth is being effected by the pressure of the bit 16. In other words the clamp which is actuated by the bit carrying plunger serves to resist any tendency of the saw blade to tilt or rock under the pressure of the setting bit upon the tooth of the saw and insure the deflection of the latter to the proper angle so as to secure uniformity in the adjustment of the saw teeth.

The cap or cover 12 is provided with marginal openings 37 for engaging studs 38 on

the walls of the stock and a central opening 39 for the reception of a threaded pin 40 on a partition 41 in which is formed the guide opening 17, said pin being engaged by a nut 42 to secure the cap in place.

It will be observed that not only the stock with its connected stationary grip member but also the movable grip member and the cap or cover may be struck or stamped from sheet metal of a suitable gauge, so as to minimize the cost of manufacture of the device without sacrificing the strength thereof.

Having described the invention, what is claimed as new and useful is:—

1. A saw set having a hollow stock extended to form a stationary grip member, a movable complemental grip member mounted upon the stock, a bit carrying plunger 20 mounted in the stock, an anvil block arranged in the path of movement of said plunger, operative connections between said movable grip member and the plunger, a retracting spring in surrounding relation to the plunger, and a saw blade engaging clamp slidably mounted in the stock and provided with a right-angularly disposed ear through which the plunger extends, the plunger being provided with a transverse pin abutting said 30 ear on one side and with a collar abutting the ear on the other side and receiving the thrust of the spring.

2. A saw set having a hollow stock extended to form a stationary grip member, a

movable complemental grip member mounted upon the stock, a bit carrying plunger mounted in the stock, an anvil block arranged in the path of movement of said plunger, and operating connections between said movable grip member and the plunger, 35 said plunger having a retracting spring and a saw blade engaging clamp being slidably mounted in the stock and provided with an ear engaged with the plunger for movement therewith toward the plane of a 40 saw blade in contact with the anvil block, the bit end of the plunger being arranged in a plane slightly in advance of the corresponding end of said clamp.

3. A saw set having a hollow stock extended to form a stationary grip member, a movable complemental grip member mounted upon the stock, a bit carrying plunger mounted in the stock, an anvil block arranged 50 in the path of movement of said plunger, a bell-crank lever pivotally mounted within the stock and having one of its arms engaging said plunger, the said movable grip member being in transversely telescoping relation with said standard grip member 55 and provided with an arm extending into the stock and having a pin and slot connection with the remaining arm of the bell-crank lever.

In testimony whereof he affixes his 60 signature.

ALOIS STAUBACH.
